TURKEY SADDLE OR SIMILAR ARTICLE

Delmont D. Brown, North Baltimore, Ohio, assignor to The D. S. Brown Company, North Baltimore, Ohio, a corporation of Ohio

Application October 24, 1955, Serial No. 38,527

Term of patent 14 years

(Cl. D12—2)

FIG. 1

FIG. 4

Fig. 1 is a top plan view of a turkey saddle or similar article showing my new design;

Fig. 2 is a cross-sectional view thereof taken on line 2—2 of Fig. 1, to show the surface contour;

Fig. 3 is a longitudinal sectional view thereof taken on the line 3—3 of Fig. 1, to further show the surface contour; and

Fig. 4 is a longitudinal sectional view thereof taken on line 4—4 of Fig. 1, to further show the surface contour.

The bottom of the turkey saddle or similar article is smooth.

I claim:

The ornamental design for a turkey saddle or similar article, substantially as shown and described.
